UNITED STATES PATENT OFFICE.

MADISON HAM, OF GLEN COVE, NEW YORK.

DAMPER-LOCK AND INDICATOR.

1,244,198.

Specification of Letters Patent. Patented Oct. 23, 1917.

Application filed March 15, 1917. Serial No. 155,106.

To all whom it may concern:

Be it known that I, MADISON HAM, a citizen of the United States, residing at Glen Cove, L. I., in the county of Nassau, State 5 of New York, have invented certain new and useful Improvements in Damper-Locks and Indicators; and I do hereby declare the following to be a full, clear, and exact description of the invention, such as will enable others skilled in the art to which it 10 pertains to make and use the same.

This invention relates to improvements in stove or furnace dampers and is directed more particularly to a safety damper lock 15 and indicator.

An object of the present invention resides in the provision of an appliance of the above nature embodying means of novel construction and arrangement by which the damper 20 may be locked in various positions of adjustment and be thus securely held against accidental displacement as well as effectively protected from unauthorized tampering.

The invention further resides in such an arrangement of the damper locking mechanism as that certain of the elements thereof 25 constitute an accurate and readily discernible indicator by which the position of the damper may be determined at a glance.

With the above and other objects of similar nature in view, the invention consists in the construction, combination and arrangement of parts set forth in and falling within 30 the scope of the appended claim.

In the drawing:

Figure 1 is a front elevation of a section of a stove pipe with the invention associated therewith and in locked position,

Fig. 2 is a side elevation thereof,

Fig. 3 is a view similar to Fig. 1 with the parts in position to permit of adjusting the damper,

Fig. 4 is a vertical section taken on the line 4—4 of Fig. 1,

Fig. 5 is a vertical section taken on the line 5—5 of Fig. 2, and,

Fig. 6 is a horizontal section taken on the line 6—6 of Fig. 1.

Referring now more particularly to the accompanying drawing, there is conventionally shown a section of stove pipe A, the invention being indicated generally at B as associated with the pipe.

Journalized transversely of the pipe A is a rod 5, one end of which is extended

through the pipe as indicated at 5'. Mounted upon the rod 5 is a damper plate 7 which may be any preferred type and is adapted for adjustment in the usual manner within 60 the pipe A.

Arranged exteriorly of the pipe and secured thereto by any desired means, are a pair of vertically spaced brackets 8 by means of which is fixedly supported a plate 9. An opening is provided in the plate 9, and has journaled therein the extended end 5' of the rod 5, said end being continued beyond the outer face of the plate and carrying a crank arm 6 by which the damper plate 7 is adjusted. The arm 6 is provided at its inner end with an enlarged head having a transverse bore receiving the extended end of the rod, set screws 16 being engaged through said head to secure 70 the arm in place. A handle 17 provided on the arm facilitates its manipulation, the arm swinging across the face of the plate 9 when moved to control the damper.

For holding the crank arm and consequently the damper plate in its various positions of adjustment, there is hinged to the plate 9 as indicated at 10, a segmental plate 11 the face of which is normally disposed in contact with the plate 9, being provided with a plurality of notches 12 extending radially with respect to the rod 5 and adapted to receive interchangeably, the free end of the crank arm 6. A staple 13 is carried by the plate 9 and arranged to pass loosely 85 through a slot 14 formed in the segmental plate 11 so that a padlock 15 may be engaged therewith to lock the plates together as clearly illustrated.

In order to manipulate the crank arm 6 95 for adjusting the damper plate 7, it is first necessary to unlock and remove the padlock 15, the segmental plate being then swung downwardly and outwardly to disengage it from the arm, after which the latter may be readily turned. When the desired adjustment is effected, the segmental plate is again swung upwardly and locked to positively maintain the adjustment of the damper, accidental displacement as well as unauthorized tampering with the damper being effectively prevented as will be evident.

It will further be noted that the segmental plate is provided on what is nominally its outer face with a plurality of suitable designations to correspond with the

notches 12 so that the position of the damper may be readily noted, the crank arm 6 serving as an indicator or pointer for this purpose.

- 5 If desired the words Gas, Danger, Damper Closed may be delineated upon the face of the plate 9 as illustrated in Fig. 1 to indicate when the crank arm 6 is engaged in either of the notches designated 12, that 10 the damper is closed and it is in consequence dangerous to attempt to kindle a fire because of the excessive coal gas generated.

What I claim is:—

- 15 The combination with a stove pipe, of a rod journaled transversely thereof, a crank

arm fixed to the rod outwardly of the pipe, a damper plate carried by the rod for adjustment within the pipe, a fixed plate, a plate hinged to the fixed plate and provided with a plurality of radially extending notches arranged to interchangeably receive the crank arm and adapted with the fixed plate to hold said arm in various positions of adjustment, and means for locking said plates in holding position. 20 25

In testimony whereof, I affix my signature, in the presence of two witnesses.

MADISON HAM.
